FURNACE CARRIER

Russell J. Williams, Chicago Heights, Ill., assignor to American Manganese Steel Company, Chicago Heights, Ill., a corporation of Maine

Application January 8, 1934, Serial No. 705,755

2 Claims. (Cl. 263—8)

This invention relates to carriers mounted upon conveyors, such as chains or the like, in sub-hearth passageways of a heat treating furnace, and projecting through slots into the heating chamber of the furnace where they receive and serve as a vehicle for sheets or other forms of metal while in the furnace.

The slots through which the carriers project, for reasons of heat economy and protection of the conveyors in the sub-hearth passages, are of restricted transverse dimensions and this correspondingly narrows the field of design for those portions of the carriers which extend through the slots. On the other hand, the relatively soft condition of the treated goods at their highest temperatures requires that the tread of the carrier be horizontally extended within the chamber to multiply its points of support and prevent sagging of intermediate portions of the goods by gravity. A third condition which must be taken into account in designing carriers for the purpose stated, is the rapid impairment of the carrier due to high ranges of expansion and contraction, if its design is such as to invite unequal stresses or stresses at points where abrupt changes in dimensions occur.

The object of the present invention is to provide carriers having materially enlarged areas of support for the heat treated material, but designed in accordance with a principle that substantially eliminates destructive stresses at high temperatures.

The invention proceeds generally upon the principle of having the carrier, and particularly its shank which projects through the hearth slot and its material-receiving head with its arm or arms providing the enlargement or enlargements within the heating chamber through which it multiplies its points of support for the goods, constructed with a transverse dimension or thickness that is either uniform throughout or varies so gradually that it is free from offsets or abrupt changes; any changes in direction of its said shank and tread or the part connecting them together being effected through curves instead of angles, so that expansion and contraction in the direction of said extensions may be transmitted with an effect approximating that which would obtain if the piece were straightened into a single plane; and the structure as a whole, or at least the shank and tread portions, being such that if these parts were straightened into a plane they would be substantially in the relation of parts connected end to end in one single plate-like piece. An incidental application of this principle

obtains where, for the sake of balancing the load upon the shank, the portion of the shank beyond the slot is deflected from the plane of the shank to meet one branch of the extended tread, and this deflected portion meets the shank and tread which it unites, through curved lines and avoids angular or abrupt changes of direction.

In the accompanying drawings, in which, several embodiments of the invention are shown by way of illustration—

Figure 1 is a plan view of one form of carrier, according to which an intermediate portion of the tread is mounted immediately over the shank, with a slight torsional deflection therefrom, and is extended in opposite horizontal directions with curvature in affording extended points of support.

Figure 2 shows one wall of a furnace slot together with a portion of a chain conveyor and two carriers mounted thereon, the form of the carriers corresponding to that shown in Figure 1.

Figure 3 is a view of parts shown in Figure 2, in a plane at right angles thereto.

Figure 4 shows a fragment of a furnace hearth constructed with a plurality of slots together with a number of carriers of the form shown in Figure 1 arranged therein in a manner to illustrate the development of an extended field of support for a sheet that is to be heat treated.

Figures 5 and 6 are, respectively, a plan view and a side elevation of a form of support which embodies the principle of the present invention and comprises a pair of tread branches connected by curved portions to each other and to the shank or an intermediate tread portion in vertical continuation of the shank so that the load is balanced thereon; Figure 6 showing in dotted lines the appearance of the tread extension if straightened from its volute form.

Figures 7, 8 and 9 are, respectively, a plan view, a side elevation and an end elevation of another design of carrier embodying the principle of the invention, in which two spaced tread members, united by a curved portion, are related to the shank portion in a manner to balance the load thereon; the shank portion being connected with one branch of the tread by a web deflected laterally to the said parts.

Referring to Figures 1 to 4, A represents a portion of a furnace hearth having slots B communicating with the sub-hearth space C, in which are assumed to be mounted conveyor chains such as D and through which are made to project shanks 1 of carriers E which are connected at their lower ends, through bolts 2 or other suit-

able means, to the chains D and are fashioned at their upper ends to the sheet or other goods-receiving treads 3.

The conveyor chain and its connection with the lower ends of the shanks 1 may be of any approved design. For instance, assuming the chain to be made up of outside links D' and inside links D2, the carriers may be conveniently mounted thereon through spaced upstanding flanges D3 on the inside links entering into bearing with bolting lugs 2a, loading lugs 2b and spacing lugs 2c. Shanks 1, in order to properly travel in the slots B, which are made narrow to conserve heat and protect the conveyor chains, are of flat plate-like form, preferably with hollow central portions 1a to reduce tendency to distortion under heat; but above the hearth A the shanks may, so long as they preserve uniform or approximately uniform dimension, be deflected or diverted to meet conditions encountered in developing a suitable expanse of tread 3.

According to Figures 1 to 4, the tread comprises an intermediate portion substantially continuing the thickness of the tread but distorted from the plane thereof to any desired angle by torsional deflection of the portion of the shank beyond the hearth, and having extensions 3b connected through curved portions 3c edgewise with the intermediate portion 3a so as to largely 25 multiply the points of support in the plane of the goods. By curving the extensions 3b, they may be brought into a direction transverse, or at some other large angle, to the direction of travel and thus enhance driving effect without introducing complications which might result from too long a dimension in the direction of travel when the carrier enters upon its swinging motion at the end of its traverse, besides making a desirable design of tread member for the carrier when assembled in a field of support as illustrated in Figure 4.

From the foregoing, it will be seen that the present invention contemplates a furnace carrier having a shank portion and a tread portion, 45 with an extension or extensions multiplying the area of support; which tread portion and extension or extensions form continuations of the shank portion without material change in thickness, and with the several parts related, so far as concerns expansion and contraction, practically as one continuous piece of plate metal.

In Figures 5 and 6, the shank portion 1x, or the vertical continuation 3x thereof, is extended at 1x' by curved portion 3x' to meet one branch 3x' 55 of a tread portion, which in turn is united by a

curved portion 3x³ to a second branch 3x⁴ spaced on the opposite side of the central tread portion 3x or shank 1x. Here, again, the parts, so far as concerns the effects of expansion and contraction, are one continuous piece of plate metal, without abrupt changes in either thickness or direction, and with a design that will balance the load upon the shank.

In Figures 7, 8 and 9, the shank portion 1y is continued upwardly and in a deflecting direction 10 by a portion 3y¹ to meet the branch 3y² of the tread with which the deflection 3y² also merges edgewise; and the branch 3y² is connected by curved portion 3y³ with a second branch 3y⁴ symmetrically spaced from the shank 1y with 15 the branch 3y² so that the load is balanced on the shank. Here, again, the construction, with respect to expansion and contraction, will effect a single continuous piece of plate metal.

While the preferred embodiment is that shown 20 in Figures 1 to 4, the modified construction shown in Figures 5 and 6, and that shown in Figures 7 to 9, will serve to illustrate some other applications in which the principle of the invention may be embodied.

What is claimed is:

1. A material carrier for conveyors for heat treating furnaces, comprising a shank having means for securing it to a conveyor, and a head supported by said shank, forming with said shank 30 an integral plate-like structure and having a material-receiving tread surface, and an integral arm extending from the plate-like carrier, in the plane thereof, arcuately deflected laterally from said plane and provided with a material-receiving 35 tread-surface which by such deflection is presented in a position laterally offset from the receiving tread of the head and thereby adapted to prevent sagging of treated material resting upon the head. 40

2. A material carrier for conveyors for heat treating furnaces, comprising a shank having means for securing it to a conveyor, a head supported by said shank and forming therewith an integral plate-like structure, and integral arms 45 extending from opposite ends of the plate-like structure in the plane thereof and arcuately deflected in opposite lateral directions from said plane; said arms being provided with material-receiving tread surfaces which by their deflection 50 are presented in positions spaced laterally from the shank and thereby adapted to prevent sagging of treating material resting upon the carrier.
